CLAIM

The ornamental design for packaging for snack pack, as shown and described.

DESCRIPTION

The patent or application file contains at least one drawing executed in color. Copies of this patent or patent application publication with colored drawing(s) will be provided by the Office upon request and payment of the necessary fee.

The sole FIGURE is a top view of a packaging for snack pack embodying my new design.

The dot-dash lines shown in the drawing represent fold lines which form no part of the claimed design.

Turtle chips is a registered trademark from Orion Corporation forming part of the claimed design.
